OIL-SEAL PULLER TOOL

Roy N. Bowden, 143 Washington St., Morristown, N.J.

Filed Dec. 26, 1963, Ser. No. 77,932

Term of patent 14 years

(Cl. D54—13)

FIGURE 1 is a side, isometric view of an oil-seal puller tool embodying my new design;

FIGURE 2 is a top plan view thereof; and

FIGURE 3 is a side elevational view showing the two outer fingers of the tool.

The dominant features of my new design reside in the portions shown in solid lines.

I claim:

The ornamental design for an oil-seal puller tool, as shown and described.
